UNITED STATES PATENT OFFICE.

JAMES E. SANDERS, OF GORDON, GEORGIA.

FIRE SCREEN.

1,425,341.

Specification of Letters Patent. Patented Aug. 8, 1922.

Application filed June 6, 1921. Serial No. 475,547.

To all whom it may concern:

Be it known that I, JAMES E. SANDERS, a citizen of the United States, residing at Gordon, in the county of Wilkinson and State 5 of Georgia, have invented certain new and useful Improvements in Fire Screens, of which the following is a specification.

This invention relates to fire screens, and the primary object of the invention is to 10 provide an improved guard for open fire places and the like, for absolutely precluding the possibility of persons or their wearing apparel coming into contact with the burning fuel or flame, and thereby rendering the fire place safe for children playing around the same.

Another object of the invention is to provide an improved fire screen arranged to 20 completely cover a fire place, and having means for rigidly securing the same in position, whereby accidental displacement thereof will be prevented, the screen having a hinged door associated therewith, whereby fuel can be readily placed on the grate or 25 andiron.

A further object of the invention is to provide a novel means for holding the cover in place against accidental opening, and a novel means for holding the cover in an 30 open position for supporting articles adjacent to the grate, whereby the articles can be warmed by the heat radiating from the grate.

With these and other objects in view, 35 the invention consists in the novel construction, arrangement and formation of parts, as will be hereinafter more specifically described, claimed and illustrated in the accompanying drawings, forming a part of 40 this application, in which drawings:

Figure 1 is a perspective view of the improved screen.

Figure 2 is a detail perspective view of 45 one of the members utilized for holding the pivoted cover of the screen in normal position against accidental opening movement.

Figure 3 is a detail perspective view of 50 the means utilized for connecting the door or cover with the body portion of the screen.

Figure 4 is a detail perspective view of 55 one member utilized for holding the cover or door in its open extended position, for holding articles to be warmed.

Figure 5 is a vertical section through a

fire place, showing the improved screen in 55 position in relation thereto.

Figure 6 is a detailed perspective view of one of the attaching arms.

Referring to the drawings in detail, wherein similar reference characters designate 60 corresponding parts throughout the several views, the letter A indicates the improved fire screen; and B, a fire place with which it can be associated.

The fire place B as shown, includes the 65 grate basket 10, the chimney 11, and the hearth 12.

The screen A is preferably formed from woven wire mesh of the desired gauge, and includes the front wall 15 and the side walls 70 16. The side walls 16 are formed integral with the front wall 15, and have their upper edges inclined upwardly as at 17. A top wall or cover 18 is provided for the screen, and is adapted to abut against the upwardly 75 inclined edges of the side walls 16, and the upper edge of the front wall 15.

If so desired, the edges of the screen, from which the fire screen is made, may be reinforced, and as shown suitable metallic bands 80 19 are connected to the marginal edges of the front wall 15, the side walls 16, and the top wall or cover 18.

The top wall 18 is preferably hingedly connected in place, in order that fuel can 85 be readily placed in the grate basket 10, without the necessity of removing the fire screen from in front of the fire place. In order to hold the upper wall 18 in place, suitable hinged members 20 are provided. 90 As shown these members 20 are connected respectively to the upper edge of the front wall 15, and at the lower forward edge of the top wall 18.

In order to prevent the accidental opening movement of the top wall or cover 18, suitable spring clips 21 are provided. These spring clips 21 include an attaching base 22 which is riveted or otherwise secured to the reinforcing member carried 100 by the upper edge of the side wall 16, and an inwardly extending off-set spring tongue 23, which is adapted to engage and overlie the upper surface of the top wall or cover 18. This is clearly shown in Figure 1 of 105 the drawings, and it is evident that accidental opening movement of the wall or cover 18 will be prevented. If so desired,

the upper ends of the spring tongues 23 may be turned back as at 24 in order to facilitate the swinging back of the tongues 23 when the cover or top wall 18 is moved 5 to its closed position.

By referring to Figure 5 of the drawings, it can be seen that the improved screen rests upon the hearth 12, and that the rear edges of the side walls 15 engage the sides 10 of the chimney or mantel piece, while the rear upper edge of the top wall 18 engages the chimney. This completely encloses or houses the fire grate, and in order to prevent accidental displacement of the screen 15 from this position, suitable retaining members 25 are provided. These retaining members 25 include a longitudinally extending body 26 which has its outer terminal coiled to provide an eye 27, which receives one of the strands of wire from which the fire screen is made. The inner end of the body 26 is preferably flattened as at 28, and provided with a suitable aperture 29 for the reception of a fastening element 30', which can be extended into the fire grate 10, as clearly shown in Figure 5 of the drawings.

In some instances, it is desirable to hold the upper wall or door 18 in a horizontal position, so that articles can be placed thereon, in order to become heated by the heat radiating from the fire place. In order to permit the top wall or cover to be held in its horizontal position, as shown 35 in dotted lines in Figures 1 and 2, arms 30 are provided. The inner end of each arm is connected by means of a hinge pin 31 with a base plate 33, which is riveted or otherwise secured to the front wall 15 adjacent to the upper edge thereof. It can be seen that these arms 30 can be swung out 40 at right angles to the front wall 15, when so desired, and thus effectively support the top wall or cover 18 in horizontal plane. 45 This will form an effective table or supporting leaf for articles which are to be heated. It also can be seen that damp clothes or the like can be laid on the arms when it is desired to quickly dry the same.

The arms can be moved toward the front 50 wall 15 of the screen and thus the clothes to be dried can be moved in relatively close proximity to the fire grate.

From the foregoing description, it can be seen that a fire screen has been provided 55 for open fire places and the like, which is of exceptionally simple and durable construction, and which can be readily and quickly associated with fire places, and which will absolutely preclude accidents 60 caused by persons falling into or coming into contact with the fire grate. It also can be seen that the screen forms an effective means for supporting articles, when it is desired to heat the same by the heat radiating from the fire grate.

Changes in details may be made without departing from the spirit or scope of this invention; but,

I claim:

1. In a fire screen for open fireplaces, a body including an open mesh front wall and a top wall, means hingedly securing the inner edge of the top wall to the upper edge of the front wall, supporting arms hingedly secured to the front wall adjacent to the upper edge thereof, for movement toward the open mesh front wall for holding articles to be dried in close proximity thereto and for movement away from the front wall for holding the top wall in a horizontal plane whereby articles to be heated can be disposed thereon.

2. In a fire screen for open fire places, a body including a foraminous front wall and foraminous top wall, means hingedly securing the outer edge of the top wall to the upper edge of the front wall, supporting arms, means hingedly securing the supporting arms to the front wall inwardly of the side edges thereof whereby articles to be dried placed upon said arms will be disposed in close proximity to the central portion of the fire place, the arms being adapted for movement at right angles to the front wall for supporting the top wall in a horizontal plane.

JAMES E. SANDERS.
